US00D991216S

(12) **United States Design Patent** (10) Patent No.: **US D991,216 S**
(45) Date of Patent: ** Jul. 4, 2023

(54) **WIRELESS HEADSET**

(71) Applicants: **Shenzhen Grandsun Industrial Design Co., Ltd.**, Shenzhen (CN); **Shenzhen Grandsun Electronic Co., Ltd.**, Shenzhen (CN)

(72) Inventors: **Jiugao Peng**, Shenzhen (CN); **Ruiwen Shi**, Shenzhen (CN); **Chuan Wang**, Shenzhen (CN); **Haiquan Wu**, Shenzhen (CN)

(73) Assignees: **Shenzhen Grandsun Industrial Design Co., Ltd.**, Shenzhen (CN); **Shenzhen Grandsun Electronic Co., Ltd.**, Shenzhen (CN)

(**) Term: **15 Years**

(21) Appl. No.: **29/805,011**

(22) Filed: **Aug. 24, 2021**

(30) **Foreign Application Priority Data**

Jul. 6, 2021 (CN) 202130422862.4

(51) LOC (14) Cl. **14-01**

(57) **CLAIM**

The ornamental design for a wireless headset, as shown and described.

DESCRIPTION

FIG. 1 is a front perspective view of a wireless headset showing the new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings are for the purpose of illustrating portions of the wireless headset that form no part of the claimed design.

1 Claim, 8 Drawing Sheets
